*Inv. No. 1,498,586
John Roy Stark
Williams, Broadbent, & McCauley Atty.*

UNITED STATES PATENT OFFICE.

JOHN ROY STARK, OF RACINE, WISCONSIN, ASSIGNOR TO WEBSTER ELECTRIC COMPANY, OF RACINE, WISCONSIN, A CORPORATION OF WISCONSIN.

IMPULSE STARTER.

Application filed October 6, 1920. Serial No. 415,206.

To all whom it may concern:

Be it known that I, JOHN ROY STARK, a citizen of the United States, and resident of Racine, in the county of Racine and State of Wisconsin, have invented a certain new and useful Improvement in Impulse Starters, of which the following is a full, clear, concise, and exact description, reference being had to the accompanying drawings, forming a part of this specification.

My invention is concerned with the provision of a so-called "impulse starter" capable of being used in connection with an internal combustion engine ignition magneto, it being the function of the impulse starter, prior to the creation of each ignition spark, at the moment of starting, and at low engine speeds, to cause the armature or rotor of the magneto to be locked against movement by the engine, released, and then moved rapidly at a speed independent of engine speed through a definite angle under the tension of a spring in which energy has been stored by the engine during the time interval that the said armature or rotor is locked against movement by the engine.

Those features of construction which characterize my present invention are particularly applicable to impulse starters embodying the invention disclosed in Patent No. 1,246,312, granted to Nero and Pontus Ostenberg, on November 13, 1917.

In the accompanying drawings illustrating my invention—

Figure 1 is a front elevational view illustrating the impulse starter of my invention applied to an ignition magneto.

Figure 2 is a vertical sectional view taken on the line 2—2 of Figure 1, and looking in the direction indicated by the arrows.

Figure 3 is a vertical sectional view taken on the line 3—3 of Figure 2, and looking in the direction indicated by the arrows.

Figure 4 is a view similar to Figure 3, illustrating the several parts of the impulse starter in the positions occupied thereby, immediately prior to the release of one of the locking pawls from the abutment afforded by the fixed impulse starter housing.

Figure 5 is a vertical sectional view taken on line 5—5 of Figure 2 and looking in the direction indicated by the arrows.

Figure 6 is an isolated view in perspective of the fixed housing.

Figure 7 is an isolated view in perspective

of the driven element of the impulse starter, and

Figure 8 is an isolated view in perspective of the driving member of the impulse starter.

Similar characters of reference refer to similar parts throughout the several views.

Referring first to Figure 1, at 10 I have illustrated a rotary ignition magneto, which, so far as my invention is concerned, may be of any suitable type. The magneto comprises the usual armature or rotor shaft illustrated at 11.

The several parts of the impulse starter are enclosed within a fixed housing 12 illustrated in perspective in Figure 6. This housing, which is formed in one piece, comprises the wall 12^a, which is provided with annular flange 12^b. Wall 12^a is provided with a central aperture 12^c for the reception of armature shaft 11, and with a plurality of openings 12^d for the reception of the screws 13—13, wherewith the housing 12 is rigidly attached to the magneto frame, as shown in Figures 1 and 2. Openings 12^d are preferably counterbored so that the heads of screws 13—13 lie flush with the inner surface of wall 12^a. Attention is directed to the fact that wall 12^a and flange 12^b are conformed to provide an offset recess 12^e, one of the inclined end walls of which, indicated at 12^f, constitutes an abutment for the locking pawls presently to be described. When housing 12 is secured to the magneto frame as illustrated in Figure 2, the said housing provides a chamber open only on that side of the housing away from the magneto frame.

The driving element of the impulse starter is indicated at 14 and is shown in isolated perspective in Figure 8. This driving member is formed in one piece, and comprises the wall 14^a provided with an annular flange 14^b, the outer diameter of which is substantially equal to the inner diameter of the flange 12^b, of fixed housing 12, so that flange 14^b may fit snugly within flange 12^b, for rotary movement therein. Wall 14^a is provided with a central aperture 14^c and is also provided with a pair of driving lugs 14^d, which are adapted to co-operate in a well-known manner with means driven by the engine with which the magneto is associated. Cut in the flange 14^b are the oppositely located notches 14^e, the said notches

being of equal and considerable depth, each notch in length representing approximately 75 degrees on the annular flange 14^b. It will be noted that the metal of the flange 14^a is beveled at 14^f—14^f. As will presently appear, the beveled surfaces 14^f—14^f serve as wedges to disengage the locking pawls from the abutment 12^f of the fixed housing 12. Flange 14^b is furthermore provided with an aperture 14^g to facilitate attachment of the driving member to a clock spring as will presently be explained.

The driven element of the impulse starter is designated at 15 and is illustrated in isolated perspective in Figure 7. The said driven member comprises the disc 15^a having a central opening 15^b and is provided with a suitable key slot so that the said driven member may be keyed upon the armature shaft as is shown in Figure 2. It will be noted that the thickness of disc 15^a is less than half the depth of the notches 14^e of the driving member and that disc 15^a is provided with lugs 15^c—15^c, which extend into the notches 14^e when the parts are assembled as shown in Figure 2. Disc 15^a has formed integral therewith a hollow, cylindrical boss 15^d, this boss being disposed concentric with the aperture 15^b and being provided with a slot 15^e for the reception of one end of the clock spring. Projecting from that face of disc 15^a opposite the boss 15^d are a pair of diametrically opposite pins 15^f, which serve to carry the locking pawls.

The clock spring is illustrated at 16. This spring lies around boss 15^d with one end thereof engaging in slot 15^e and the other end thereof engaging in the opening 14^g of the driving member. It should be noted that the flange 14^b is milled on its outer surface at a point adjacent the aperture 14^g so that the outer end of spring 16 will not project beyond the outer cylindrical surface of flange 14^b. Prior to the assembly of the driving and driven members, the spring 16 is given a certain amount of initial tension, so that the spring normally tends to urge the driven member in the direction of armature rotation, thereby holding the lugs 15^c—15^c in those ends of the driving member notches opposite the beveled surfaces 14^f, 14^f.

The pawls 17—17 are formed of flat pieces of steel provided with suitable apertures to receive the pins 15^f—15^f of the driven member 15. It will be noted that the trailing heavy ends of the pawls are conformed so that they may, under certain circumstances, lie against and partially around the small annular flange 15^g, said flange 15^g being formed integral with the driven member and bounding the central aperture 15^b thereof. The shape of each of the pawls is such that whenever the long, trailing end of one of the pawls lies in engagement with

flange 15^g, the nose of the pawl is projected through one of the notches 14^e of the driving member.

When the parts are assembled as shown in Figure 2, the boss 15^d of the driven member lies in the opening 14^g of the driving member and the spring 16 lies in the annular space between the disc 15^a and the wall 14^a. Displacement of the pawls from the pins 15^f—15^f is prevented by the wall 12^a of the fixed housing 12. In order to prevent the ingress of dust, a drawn metal cup 18 is fitted into the hollow boss 15^d of the driven member. This cup is provided with a central aperture to receive the end of the armature shaft and is held in position by a nut 19. It will be noted that the cup 18 is provided with an annular flange 18^a, which overlaps the space between the boss 15^d and the wall 14^a of the driving member, the said wall 14^a preferably being provided with an annular seat to receive said flange, as is clearly shown in Figure 2.

In Figures 1, 3 and 4, the arrows indicate the direction in which the driving member is rotated by engine driven means co-operating with lugs 14^a—14^a. Now let us assume that the driving member is being rotated at low speed. Rotation of the driving member 14 is transmitted through the spring 16 until the nose of one of the pawls 17 goes into engagement with the abutment 12^f of the fixed housing 12. Provided the parts are rotated at low speed, each of the pawls will engage the abutment 12^f, whenever said pawl reaches the position occupied by the upper pawl in Figure 3, this engagement being insured because the heavy, trailing end of the pawl gravitates to a position against the flange 15^g, and thus forces the nose of the pawl out through the adjacent notch 14^e. After the nose of one of the pawls engages abutment 12^f as shown in Figure 3, further movement of the driving member is taken up by the spring 16 until one of the beveled surfaces 14^f of the driving member flange 14^b engages the nose of the pawl as shown in Figure 4, and disengages the pawl from the abutment. As soon as this disengagement is effected, the spring serves rapidly to rotate the driven member ahead of the driving member until such movement is stopped by engagement of the lugs 15^c—15^c with the driving member flange 14^b. So long as the driving member continues to rotate at slow speed, the operation just described occurs twice during each revolution of the driving member. The intermittent rapid rotary movements which are thus imparted to the armature result in the generation of effective ignition currents in a manner, and for the reasons, well known to persons familiar with the art to which my invention relates.

When the driving and driven members

are rotated at high speed, the heavy trailing ends of the pawls 17-17 are held out against the flange 14^b of the driving member by centrifugal force. In this case, the 5 pawls do not engage the abutment of the fixed housing and continuous rotary movement is imparted to the driven member from the driving member through the clock spring.

10 Having thus described my invention, what I claim is new and desire to secure by Letters Patent is:

1. An impulse starter comprising a housing consisting of a centrally apertured wall, 15 provided with an annular flange, said housing adapted to be fixed to a magneto frame with the armature shaft of the magneto extending freely through the aforesaid apertured wall, said wall and flange being 20 formed to provide an offset recess, one end wall of which constitutes an abutment, driving and driven members disposed in said housing, spring means interposed between said driving and driven members, a pawl 25 carried by the driven member adapted to engage said abutment, and lock the driven member to the housing, when the driven member is rotated at low speed and means on the driving member for disengaging the 30 pawl from the abutment, said pawl being centrifugally actuated to an inoperative position when the driving member is rotated at high speed.

2. An impulse starter comprising a housing consisting of a centrally apertured wall, 35 provided with an annular flange, said housing adapted to be fixed to a magneto frame with the armature shaft of the magneto extending freely through the aforesaid apertured wall, said housing provided with an offset recess one end wall of which constitutes an abutment, driving and driven members disposed in said housing, the driven member adapted to be fixed to the armature 40 shaft, spring means interposed between the driving and driven members, a pawl carried by the driven member, said pawl being gravity operated to engage said abutment when the driven member rotates at low 45 speed, and centrifugally operated to an inoperative position when the driven member rotates at high speed, together with means for disengaging the pawl from the abutment when, after the engagement of the pawl and 50 abutment, as aforesaid, the driving member has been given a definite amount of rotary movement independently of the driven member.

3. In an impulse starter, a substantially 55 circular driven member provided with a peripheral lug, a driving member comprising an annular flange adapted to embrace the driven member, a notch in said flange adapted to receive the peripheral lug, the depth 60 of the notch being greater than the thickness

of the lug, spring means interposed between the driving and driven members, a pawl carried by the driven member, said pawl being gravity actuated to project the nose thereof through the notch in the flange of 70 the driving member when the driven member is slowly revolved, and centrifugally actuated to retract the nose of the pawl when the driven member is rotated at high speed, together with a fixed abutment adapted to 75 be engaged by the nose of the pawl when the latter projects through the notch of the driving member flange as aforesaid, the flange of the driving member being adapted to disengage the pawl from the abutment 80 when the driving member has been given a definite amount of movement independently of the driven member.

4. In an impulse starter, a substantially circular driven member provided with a peripheral lug, a driving member comprising an annular flange adapted to embrace the driven member, a notch in said flange adapted to receive the peripheral lug, the depth of 85 the notch being greater than the thickness of the lug, spring means interposed between the driving and driven members, a pawl carried by the driven member, said pawl being gravity actuated to project the nose thereof through the notch in the flange of the driving member when the driven member is slowly revolved, and centrifugally actuated to retract the nose of the pawl when the driven member is rotated at high speed, together with a fixed housing in which the 90 driving and driven members are disposed, said housing being provided with a fixed abutment adapted to be engaged by the nose of the pawl when the latter projects through the notch of the driving member flange as 95 aforesaid, the flange of the driving member being adapted to disengage the pawl from the fixed abutment when the driving member has been given a definite amount of rotary movement independently of the driven member.

5. In an impulse starter, a driven member adapted to be attached to the armature shaft of a magneto, a peripheral lug on said driven member, a driving member comprising an annular flange adapted to embrace the driven member, a notch in said flange, arranged to receive said lug, said notch being deeper than said lug so as to provide a projecting portion, spring means interposed between the driving and driven members, a pawl carried by the driven member, said pawl being gravity actuated to project the nose thereof through said notch in said projecting portion when the driven member is slowly revolved, and centrifugally actuated to hold the nose of the pawl retracted when the driven member is rotated at high speed, together with a fixed abutment adapted to be 120 engaged by the nose of the pawl when the 125

130

1
latter projects through the notch in the driving member flange, said flange being adapted to disengage the pawl from the abutment when the driving member has been given a definite amount of rotary movement independently of the driven member.

6. An impulse starter comprising a housing and driving and driven members disposed in the housing for rotary movement 10 therein, said housing being fixed to the end plate of the magneto frame and the driven member to the armature shaft of a magneto, a boss on that side of the driven member next adjacent the driving member, a spring 15 disposed between the driving and driven members and attached to each, a flange on the driving member adapted to embrace the driven member, a notch in said flange, a pawl carried by the driven member, and provided with a nose adapted to project 20 through said notch, an abutment carried by the housing adapted to be engaged by the nose of the pawl when the latter projects through said notch, the flange of the driving member being adapted to disengage the pawl from said abutment when the driving member has been given a definite amount of 25 rotary movement independently of the driven member.

30 7. An impulse starter comprising a fixed housing secured to the end plate of a magneto, driving and driven members disposed in said housing, said driven member adapted to be secured to the armature shaft of the 35 magneto, spring means interposed between the driving and driven members and at-

tached to each, a flange on the driving member adapted to embrace the driven member, a pawl on the driven member, the nose of said pawl adapted to project through a notch 40 in the driving member flange, a fixed abutment adapted to be engaged by the nose of the pawl when the latter projects through said notch, said driving member flange serving to disengage the pawl from the abutment when the driving member has been given a definite amount of rotary movement 45 independently of the driven member.

8. In an impulse starter, a housing member fixed to the magneto frame, an annular flange projecting from said housing, a driving member having an annular flange in close engagement with said housing flange, said housing member and said driving members serving to form a complete housing, a driven member within said housing, resilient means joining said driven member to said driving member, a fixed abutment on the annular flange of said housing, a pawl carried by said driven member and arranged 60 to engage said abutment, and means on said driving member for releasing said pawl when said driving member has moved a definite angular distance in relation to said driven member.

In witness whereof, I hereunto subscribe my name this 28th day of Sept., 1920.

JOHN ROY STARK.
